UNITED STATES PATENT OFFICE

148,514

DESIGN FOR A ROTARY DISC SURFACE
FINISHING MACHINE

Kenneth C. Atkin, Muskegon, Mich., assignor to
Clarke Sanding Machine Company, Muskegon,
Mich., a corporation of Michigan

Application July 24, 1946, Serial No. 131,880

Term of patent 14 years

(Cl. D9—2)

To all whom it may concern:

Be it known that I, Kenneth C. Atkin, a citizen of the United States, residing at Muskegon, in the county of Muskegon and State of Michigan, have invented a new, original, and ornamental Design for a Rotary Disc Surface Finishing Machine, of which the following is a specification, reference being had to the accompanying drawings, forming a part thereof.

In the drawings:

Fig. 1 is a top plan view of a rotary disc surface finishing machine showing my new design;

Fig. 2 is a side elevational view thereof; and

Fig. 3 is a front elevational view thereof.

I claim:

The ornamental design for a rotary disc surface finishing machine, substantially as shown.

KENNETH C. ATKIN,
